ANCHOR

William Wilson, Astoria, Oreg.

Application April 10, 1942, Serial No. 438,512

4 Claims. (Cl. 114—208)

This invention relates to an anchor and has for an object to provide an anchor having aligned flukes integral with the shank of the anchor and a pair of aligned integral flukes on the shank movable to operative position at right angles to the first named flukes to prevent dragging of the anchor, and movable to a position parallel with the first named flukes to permit the anchor to be stored in a minimum space.

A further object is to provide simplified means for adjusting the movable flukes to either position and holding the movable flukes in adjusted position.

A further object is to provide apparatus of this character which will be formed of a few strong, simple and durable parts, which will be inexpensive to manufacture, and which will not easily get out of order.

With the above and other objects in view the invention consists of certain novel details of construction and combinations of parts herein-after fully described and claimed, it being understood that various modifications may be resorted to within the scope of the appended claims without departing from the spirit or sacrificing any of the advantages of the invention.

In the accompanying drawings forming a part of this specification:

Figure 1 is a top plan view of an anchor constructed in accordance with the invention showing the anchor in collapsed inoperative position.

Figure 2 is a side elevation of the anchor shown in Figure 1 with portions broken away.

Figure 3 is a view similar to Figure 2 but showing the adjusting and holding means in position to permit the integral pair of movable flukes to be adjustable to operative position at right angles to the flukes carried by the shank of the anchor.

Figure 4 is a cross sectional view taken on the line 4—4 of Figure 2 but showing the adjustable flukes in operative position.

Figure 5 is a plan view of the integral adjustable flukes showing the rectangular opening therein for receiving the adjusting and holding means.

Figure 6 is a top plan view showing the shank of the anchor and the flukes integral therewith having a rectangular collar at the bottom of the shank to enter the similar shaped opening of the adjusting and holding sleeve to hold the flukes in operative or in inoperative position.

Figure 7 is a bottom plan view of the adjusting and holding sleeve.

Figure 8 is a side elevation of the adjusting and holding sleeve.

Figure 9 is a side elevation of the adjusting and holding sleeve turned through an angle of ninety degrees from the position shown in Figure 8.

Figure 10 is a side elevation of the lock nut for screws onto the adjusting sleeve and showing the latch carried by the lock nut.

Figure 11 is a side elevation of a modified form of the invention and showing a different adjusting and holding means than that shown in Figures 1 to 10 inclusive.

Figure 12 is a perspective view of the upper member of the adjusting sleeve used in the form of the invention shown in Figure 11.

Figure 13 is a perspective view of the lower member of the adjusting and holding sleeve slots which receive tongues on the upper member of the adjusting sleeve.

Figure 14 is another modified form of the invention showing another form of adjusting and holding means.

Figure 15 is a perspective view showing the inverted U-shaped bayonet groove in the shank of the anchor shown in Figure 14.

Figure 16 is a perspective view of an adjusting and holding sleeve having a bayonet slot reversed in direction relatively to, and adapted to coact with the bayonet slot in the shank.

Referring now to the drawings in which like characters of reference designate similar parts in the various views, the anchor shown in Figures 1 to 10 inclusive comprises a shank 10 provided at the upper end with a ring 11 and having a pair of aligned flukes 12 integral with the bottom. The shank is provided with a substantially rectangular collar 13 just above the flukes 12.

Disposed on the shank above the flukes 12 is a pair of aligned integral flukes 14, there being a substantially rectangular opening 15 at the integral inner ends of the flukes, see Figure 5, into which the collar 13 is loosely received.

An adjusting and holding sleeve 16 is provided with U-shaped bayonet slots 17 at diametrically opposite points thereof, see Figures 8 and 9, and above the slots the sleeve is provided with an external screw thread 18. Below the slots the sleeve is formed with a substantially rectangular neck 19 adapted to be inserted in the opening 15 of the aligned adjustable flukes 14 and engage the collar 13 to hold the adjustable flukes in either an operative position or in a released position. In operative position the adjustable flukes 14 extend at right angles to the flukes 12 which are integral with the shank 10, see Figure 4, and pre-

vent dragging of the anchor on the bottom of a body of water. In inoperative position the adjustable flukes 14 extend parallel with the flukes 12 so that the anchor will occupy minimum space in storage.

Adjustment of the adjustable flukes is effected by sliding the sleeve 16 upwardly on the shank 10 so that the neck at its lower or outer end is removed from or raised above the collar 13 and thereby disengaged from the opening in the flukes to permit turning of the adjustable flukes about the collar of the shank. For permitting such movement of the sleeve a pin 20 is engaged transversely through the shank 10 and the ends of the pin project into the bayonet slots 17 and the pin is at the upper ends of the vertical legs of the slots when the sleeve is in lowered position to engage the collar 13 for holding the adjustable flukes in adjusted position. The normal position of the pin is shown in Figure 2. When the sleeve is slid upwardly as shown in Figure 3 the pin is lodged into horizontal portions of the bayonet slots so that the rectangular neck 19 is withdrawn from the collar 13 and permits rotation of the adjustable fluke to either of the two positions whereupon the sleeve may be lowered to engage the neck with the collar and preserve the adjustment.

For controlling the sleeve a lock nut 21 is provided, this nut being preferably hexagonal in shape and provided at each of its sides with a bayonet slot 22, see Figures 4 and 10. The nut is in the nature of a cap 10, see Figure 3, having an opening 23 to receive the shank 10, and having an internal screw thread 24 to engage the screw thread 18 of the sleeve 16.

The nut 21 is adapted to be turned on the sleeve to receive the ends of the pin 20 in a pair of opposite bayonet slots 22, see Figure 2, in which position of the nut the lower sides of the bayonet slots of the nut engage underneath the ends of the pin and positively prevent the sleeve from being slid upwardly. The nut is releasably held in this position by a pivot latch 25 which is mounted on one of the faces of the nut and is provided with a detent 26, see Figures 4 and 10, which enters the vertical portion of one of the bayonet slots back of one of the ends of the pin and positively prevents rotation of the nut. However when the latch is rocked upwardly from the position shown in Figure 10 to withdraw the detent 26 from a position back of the pin, the nut may be rotated in a retrograde direction to lodge the ends of the pin in the vertical portions of the bayonet slots of the nut and permit both the nut and the sleeve being raised vertically as a unit to the position shown in Figure 3 to permit adjustment of the adjustable flukes 14 to either operative or inoperative position. When the adjustment has been made the sleeve and nut are lowered as a unit and the nut is then turned to lodge the ends of the pins in the bayonet slots 22 and then the latch is swung to lodge the detent 26 in one of the bayonet slots back of one of the ends of the pins to prevent accidental rotation of the nut.

In the modified form of the invention shown in Figures 11 to 13 inclusive the shank 27 of the anchor is provided at the lower end with a rectangular collar 28 and below the collar is formed with integral aligned flukes 29, and at the upper end the shank is provided with a ring 30, as previously described.

In this form of the invention however the adjusting and holding sleeve is formed in two sections, namely a lower member 31 which is integral

with the aligned adjustable flukes 32, and an upper member 33 which is slideably mounted on a threaded collar 34 on the shank, uniformly increased in diameter.

5 The lower member 31 is provided at diametrically opposite points with vertically disposed slots 35 adapted to receive depending tongues 36 formed on the upper member 33, see Figures 12 and 13. The upper member 33 is provided with a 10 transverse slot 37 adapted to receive a transversely disposed pin 38 carried by the shank 27.

A lock nut 39 is threadedly engaged with the shank 27 of the shank and normally bears upon the upper member 33 of the adjusting sleeve and 15 holds the tongues 36 thereof lodged on top of the lower member 31 of the adjusting sleeve, see Figure 1, to hold the adjustable flukes 32 in either operative or inoperative position.

When the nut 39 is backed upwardly on the 20 threaded shoulder 34 the pressure of the upper wall of the slot 37 on the pin 38 is relieved so that the upper member may be rotated through an arc of about ninety degrees to bring the tongues 36 into register with the slots 35. At this time the 25 lower member 31 together with the adjustable flukes 32 carried thereby may be raised vertically on the shank until the tongues reach the bottom of the slots at which time the locking rectangular opening 40 in the adjustable flukes 32 will be raised off the rectangular collar 28 and permit the adjustable flukes and both members of the adjusting sleeves to be rotated as a 30 unit so that the adjustable flukes may be brought into either released or operative position. When 35 this has been accomplished the adjustable flukes and integral lower member 31 of the adjusting sleeve are dropped down to again engage the collar 28 with the opening in the flukes and permit the upper member 33 to be rotated to again 40 bring the tongues to set on the upper end of the lower member of the adjusting sleeve whereupon the nut 39 may be tightened to hold the upper member in this position and hold the top wall of the slot 37 in engagement with the pin 38 to preserve the adjustment.

45 Another modified form of the invention is shown in Figures 14 to 16 inclusive. In this form of the invention the shank 41 of the anchor is provided at the lower end with a rectangular collar 42 and is provided above the rectangular collar with a uniformly large cylindrical collar 43. Below the collar 42 the shank is provided 50 with integral aligned flukes 45. An inverted U-shaped bayonet slot 46 is formed in the collar 43.

55 The adjustable flukes 47 have formed integral therewith an exterior adjusting sleeve 48 shorter than and slideable on an inner sleeve 49.

The outer member is provided at diametrically 60 opposite points with pins 50 which project into L-shaped bayonet slots 51 formed at diametrically opposite points in the inner member 49. When the pins project into the horizontal portion of the slots the outer member cannot be raised but when the member 49 is turned axially on the shank to bring the vertical legs of the slots into register with the pins the pins will ride up in the slots to permit the outer member being raised to adjust the adjustable flukes. Both the outer member 48 and the inner member 49 may 65 now be rotated to rotate the adjustable flukes to adjusted position, the pins 50 meanwhile riding in the horizontal portion of the inverted U-shaped slot 46 of the shank 41. When the adjustable flukes have attained their adjusted positions the members 48 and 49 will have been turned to positions

tions that will bring the pins 50 into registration with the vertical portions of the slots 46 and whereupon the member 48 may be lowered to engage the rectangular collar 42 in a rectangular opening 52 of the adjustable flukes to lock the adjustable flukes against further rotation. The member 49 may now be turned axially to lodge the pins 50 in the horizontal portion of the bayonet slot 51 of the upper member 49 and prevent dislodgement of the adjustable flukes from adjusted position.

A pin 53 is engaged through the collar 43 of the shank 41 and the ends project into respective circumferential slots 54 of the inner member. A nut 55 is engaged on a threaded portion 56 of the collar 43 and may be tightened against the member 49 to releasably lock the upper member against the pin 53 and prevent accidental rotation of the upper member.

Since the operation of the parts has been described as the description of the parts progressed it is thought that the invention will be fully understood without further explanation.

What is claimed is:

1. In an anchor having a shank, a pair of flukes integral with the bottom end of the shank, a non-circular collar on the shank at its junction with said flukes, a pair of aligned flukes pivotally adjustable on the shank having a non-circular opening at the center portion through which the collar extends, said opening being of

such size that the collar is free to turn therein to dispose the flukes integral with the shank parallel with or at a right angle with the adjustable flukes, and a sleeve axially slidable on the shank having its outer end portion shaped to fit between the shoulder and the walls of the opening for releasably effecting non-turning connection between the collar and the adjustable flukes.

5 2. In an anchor as claimed in claim 1, means 10 on the shank for limiting the movement of said sleeve, and means for releasably locking the sleeve in a position removed from the collar.

3. An anchor as claimed in claim 1 wherein 15 the sleeve is provided with U-shaped slots, a pin extended through the shank and the slots of the sleeve whereby the sleeve may be releasably held in a position removed from the collar, and means on the sleeve engageable with the pin for releasably locking the sleeve in collar engaging position.

20 4. An anchor as claimed in claim 1 wherein the sleeve is provided with U-shaped slots, a pin extended through the shank and the slots of the sleeve whereby the sleeve may be releasably held 25 in a position removed from the collar, and a nut threaded on the inner end of the sleeve having slots therein engageable with the pin for releasably locking the sleeve in collar engaging position.

30

WILLIAM WILSON.
